EDUCATIONAL TOY

George R. Abernethy, Charlotte, N. C.

Application October 4, 1941, Serial No. 413,635

4 Claims. (Cl. 46—131)

This invention relates to an educational toy and more especially to a pivotally mounted frame adapted to support a plurality of objects such as toy airplanes and the like in a radial position from the pivot point about which the objects rotate.

It is an object of this invention to provide a frame of the class described in which means are provided for quickly and easily varying the radial distance of the objects from the pivot point so that all of the moving parts will be properly balanced about the axis of rotation. Specifically the invention, in part, comprises a horizontally disposed bar having one end thereof supported by a vertical pivot, said bar having pivotally secured to an intermediate portion thereof, a pair of oppositely disposed arms. These arms project beyond the opposite side of the pivot a sufficient amount to substantially balance the weight of the arms and the bar on the pivot. In other words, the arms and the bar comprise a framework from which suitable toy airplanes or the like are suspended while the frame rotates on the pivot. In order to further balance the structure, means are provided for varying the positions of the outer ends of the arms relative to the pivot or axis of rotation. The variation of the angular position of the arms, effects a balancing adjustment because the center of gravity of the frame is thereby shifted.

Some of the objects of the invention having been stated, other objects will appear as the description proceeds when taken in connection with the accompanying drawing, in which—

Figure 1 is an isometric view of my improved educational toy;

Figure 2 is a transverse vertical sectional view taken along the line 2—2 in Figure 1;

Figure 3 is an enlarged sectional detail view taken along the line 3—3 in Figure 1, illustrating the method of mounting the frame upon its pivot;

Figure 4 is a plan view of a portion of the frame as it appears in a collapsed position;

Figure 5 is a plan view illustrating a slightly modified form of my educational toy;

Figure 6 is a vertical sectional view taken along the line 6—6 in Figure 5.

Referring more specifically to the drawing, the numeral 10 denotes a suitable base from which extends a vertically disposed post 11. This post has a pivot member 12 extending from the upper end thereof, said pivot member having a pointed upper end which is adapted to fit in one of a 55

plurality of conical cavities such as 14, 15, and 16 in a horizontal member such as a nail 17. In the present embodiment of the invention (Figure 3), the sharpened pivot member 12 is located in the cavity 14; however, other cavities might be employed, depending upon the adjustment desired. The right hand end of the nail or member 17 (Figure 3), is secured in one end of a bar 18, said bar having pivotally secured to the intermediate portion thereof as at 19, a pair of oppositely disposed channel members 20 and 21. The members 20 and 21 are disposed at an acute angle to that portion of the bar 18 between nail 17 and pivot point 19.

The bar 18 has a suitable slot 25 in its extreme outer end. Likewise each of the extreme outer ends of the arms 20 and 21 have similar slots 26 and 27 respectively. Each of the slots 25, 26 and 27 are adapted to receive an eye bolt 28 from which is suspended a wire, string or the like 29 and the lower end of this string supports an object such as a toy airplane 30. When it is desired to individually adjust the position which each airplane occupies relative to the pivot member 12, it is only necessary to adjust the eye bolt 28 in the desired slots 25, 26 or 27.

As a further means for adjusting the balance of the frame structure, means are provided for varying the angularity of the arms 20 and 21 relative to the bar 18. In order to vary this angularity, a suitable bridge member or bar 32 is provided which has a notch 33 in the intermediate portion thereof. This notch receives the bar 18 when in an installed position and at the same time, the ends of the bridge member 32 slidably and frictionally fit into the grooved channel arms 20 and 21. Bridge member 32 is deflected downwardly in the central portion, that is at notch 33, so that the natural resiliency in the member 32 will normally cause the frictional contact to be present between this notch and the member 18 and also between the lower outer ends of this bar and the channel members 20 and 21. In other words, by deflecting or bending the bar 32 in the center, a spring means is provided for normally holding or binding the members 20, 21 and 18 into a rigid frame.

If it is desired to widen the distance between the free ends of members 20 and 21, that is to increase the angularity relative to the member 18, it is only necessary to move the member 32 away from the observer in Figure 1 and thereby spread each of the arms 20 and 21 an equal amount. Of course to decrease the angularity the reverse operation must be effected. The above described

operation will simultaneously balance the weight of the arms 20 and 21 and their respective planes 30 on one side of pivot 12, against the bar 18 and its plane 30 on the other side, and thereby produce equilibrium in the rotating assembly. If desired, as for example, when some of the objects 30 differ in weight, the point 12 can be placed in cavity 15 or 16 to more easily effect a balancing operation.

Figures 5 and 6 show a slightly modified form of the invention in which like reference characters will apply to like parts and a description will be made only of the parts which differ in construction. The principal difference between the structure in Figures 5 and 6 and that of the preceding form is the manner in which adjustment of the angularity of arms 20 and 21 relative to bar 18 is effected. It will be noted that the arms 20 and 21 are normally rotated towards each other by means of a suitable tension spring 36, said tension spring having its ends connected to arms 20 and 21 as at 37 and 38 respectively.

In order to limit the inward rotation of members 20 and 21 as a result of spring 36, a suitable bridge 39 is provided, said bridge having an opening 40 therein which encircles the bar 18. The bridge also has restricted end portions 41 and 42 which fit into the channel members 20 and 21 respectively. It is seen that the adjustment of the angularity of members 20 and 21 in this form of the invention can be effected by merely sliding the bar 39 at right angles along the central bar 18 and as this operation is effected, the spring 36 will automatically hold the bar 39 in position.

When the toy is balanced and ready for operation, gradually increasing lateral pressure can be applied to the side of that portion of the nail 17 nearest the observer in Figure 1 and when the framework is rotating at the desired speed, the pressure is removed and the framework continues to rotate for a great number of revolutions due to its perfect balance and needle point suspension.

In the drawing and specification, there has been set forth a preferred embodiment of the invention, and although specific terms are employed, they are used in a generic and descriptive sense only and not for purposes of limitation, the scope of the invention being set forth in the appended claims.

I claim:

1. A toy comprising a pivot member, a substantially horizontal bar mounted near one end for rotation on said pivot member, a pair of oppositely disposed arms pivotally secured to said bar remotely from said pivot member and having the

free ends thereof extending to the opposite side of said pivot member, each of said arms forming an acute angle with that portion of said bar disposed between said pivot member and said arm pivot, and means for adjusting the angularity of said arms relative to said bar.

2. A toy comprising a pivot member, a substantially horizontal bar mounted near one of its ends for rotation on said pivot member, a pair of oppositely disposed arms having one of their ends pivotally secured to the other end of said bar and having the free ends thereof extending to the opposite side of said pivot member, each of said arms forming an acute angle with that portion of said bar disposed between said pivot member and said arm pivot, and a spacer bar having the ends thereof slidably secured along the intermediate portions of said arms whereby the angularity between the arms and the horizontal bar may be adjusted.

3. A toy comprising a pivot member, a substantially horizontal bar mounted near one of its ends for rotation on said pivot member, a pair of oppositely disposed arms pivotally secured to said bar remotely from said pivot member and having the free ends thereof extending to the opposite side of said pivot member, each of said arms forming an acute angle with that portion of said bar disposed between said pivot member and said arm pivot, and a spacer bar having the opposite ends thereof slidably secured along the intermediate portions of said arms whereby the angularity between the arms and the horizontal bar may be adjusted, the intermediate portion of said spacer bar being adapted to frictionally engage said horizontal bar to thereby bind the arms and bars into a rigid frame.

4. A toy comprising a pivot member, a substantially horizontal bar mounted near one of its ends for rotation on said pivot member, a pair of oppositely disposed arms pivotally secured at one of their ends to said bar remotely from said pivot member and having the free ends thereof extending to the opposite side of said pivot member, each of said arms forming an acute angle with that portion of said bar disposed between said pivot member and said arm pivot, and a spacer bar having the opposite ends thereof slidably secured along the intermediate portions of said arms whereby the angularity between the arms and the horizontal bar may be adjusted, and spring means for normally urging the free ends of said arms toward each other and against the ends of the spacer bar.

GEORGE R. ABERNETHY.
